ERIC OLLE SCHJOLIN, OF BIRMINGHAM, MICHIGAN, ASSIGNOR TO YELLOW TRUCK & COACH MANUFACTURING COMPANY, OF PONTIAC, MICHIGAN, A CORPORATION OF MAINE

COOLING SYSTEM

Application filed June 4, 1928. Serial No. 282,681.

This invention relates to a cooling system for internal combustion engines.

It is an object of this invention to provide a cooling system for internal combustion engines which will insure proper cooling of all parts of the engine.

It is a further object of this invention to provide in combination with the cooling system of an internal combustion engine means 10 whereby a portion of the cooling medium, after having become heated in cooling the engine, is caused to give up a portion of its heat to the incoming combustible mixture, before the introduction of the latter into the 15 cylinders, so as to aid in the vaporization thereof.

Other objects of the invention will be apparent from a perusal of the following specification taken in connection with the accompanying drawing.

In the drawing, the single figure shows a cross section through one of the cylinders of an internal combustion engine in which is embodied my invention.

25 Referring to the drawing, the reference character 10 indicates an engine of the double sleeve valve type which includes a crankcase 11 to which is secured the cylinder block 12. Within the cylinder block are provided a plurality of cylinders in each of which are provided reciprocating outer and inner sleeve valves 13 and 14 and a reciprocating piston 15. At spaced points in the walls of the cylinder, there are provided intake and discharge ports 16 and 17 which communicate, respectively, with the intake manifold 18 and the exhaust manifold (not shown). The outer and inner sleeve valves are provided at 19 and 20, respectively, with intake ports 30 adapted to register with each other and with the intake port in the cylinder wall at the proper moment to admit a charge of combustible mixture into the cylinder, and at 21 and 22, respectively, with exhaust ports 35 adapted to register with each other and with the exhaust port in the cylinder wall at the proper moment to allow the discharge of exhaust gases from the cylinder.

The upper ends of the cylinders are closed 50 by a head 23 which includes a hollow cylin-

drical portion 24 extending downwardly a considerable distance into each of the cylinders. The outer wall of each portion 24 is spaced circumferentially from the wall of the cylinder in which it is located to provide 55 a space in which the upper ends of the sleeve valves are adapted to slide. The bottom of the portion 24 is closed by a concave wall 25 which is provided centrally thereof with a threaded bore 26 surrounded by an upwardly 60 projecting cylindrical wall 27. As is shown in the drawing, a spark plug 28 is adapted to be located in the space surrounded by the wall 27 with its threaded portion in engagement with the threaded bore 26 and extending 65 therethrough into the cylinder.

The cylinders are water-jacketed, as indicated at 29, to provide passages, such as 30, through which cooling water may be circulated around the cylinders.

The head 23 is enclosed by a cover 31, which is spaced therefrom to provide a passage 32, which is in communication with the passages 30 in the block through passages (not shown), and which is also in communication with the annular cooling water spaces 33 provided in the downwardly projecting portions of the cylinder head.

The reference character 34 indicates a water pump, which is adapted to be driven in any suitable manner from the engine, and which is provided with an intake conduit 35 through which it is adapted to withdraw water from the bottom of a radiator of the type ordinarily used on automobiles. The 80 pump is also provided with a discharge conduit 36 which communicates with the connection 37 which opens into the cylinder block water jacket and through which the pump is adapted to discharge water from the radiator 85 into the cylinder block water jacket, whence it passes into the cylinder head water jacket, whence it passes, through a suitable connection 38, into the top of the radiator. There is provided in the connection 38 a butterfly 90 valve 39 which may be operated in any suitable manner to control the flow of water therethrough.

It is well known that the portions of the cylinder head above the piston—i. e., the de- 100

pending portions of the cylinder head—are subjected to higher temperatures than any other part of the engine and that they are more difficult to cool, since it is difficult to provide for a proper circulation of water through these depending portions. To insure proper circulation of water through the depending portions of cylinder head and at the same time to provide for heating the combustible mixture supplied to the cylinders of the engine prior to its introduction into the cylinders, I provide a jacket 40 around the intake manifold 18, and pipes 41, each of which opens at one end adjacent the bottom of one of the annular spaces 33 in the depending portions 24 of the cylinder head and all of which communicate, through passages 42 in the cylinder block, with the interior of the jacket 40 around the intake manifold. The jacket around the intake manifold also communicates with a pipe 43 which opens into a second intake conduit 44 provided on the pump 34.

The above described structure operates as follows (assuming that the valve 39 is open so as to allow the passage of water through the connection 38): When the engine is turned over, the pump 34 starts operating and draws water from the radiator through the conduit 35 and forces it through the conduits 36 and 37 into the passages 30 around the cylinder block, thereby cooling the block. From the passages 30 the water passes, through the hereinbeforementioned openings, into the passage 32 and the spaces 33, whence part of it passes, through the connection 38 back into the radiator, whence, after being cooled, it is redrawn and recirculated by the pump. As will be clear, the suction of the pump on the intake conduit 44 will cause a portion of the water which flows into the spaces 33, and, therefore, attains a maximum temperature, to be withdrawn therefrom, through the pipes 41, the passage 42, the intake manifold jacket 40, the pipe 43 and the conduit 44 directly back into the pump where it will be mixed with the cooler water from the radiator and re-circulated therewith. It will be obvious that the withdrawal of a portion of the heated cooling water and its return to the pump through the pipes 41 and associated passages accomplishes a double function. Firstly, it insures a positive circulation of water through the depending portions of the cylinder head whereby they are efficiently cooled, and secondly, it provides for the use of a portion of the heat absorbed by this water in the course of its circulation through the engine to heat the incoming combustible mixture thereby aiding in vaporizing it. It is obvious that, if desired, a by-pass may be provided, whereby, at will, the cooling medium withdrawn from the recesses in the cylinder head through the pipes 41 may be returned to the pump with-

out passing through the intake manifold jacket.

It will be obvious that the valve 39 can be adjusted to control the amount of cooling water circulated through the radiator. If it is entirely closed, no water will circulate through the radiator. In this event the pump will circulate and recirculate the same water through the engine water jackets, and the pipes 41, the passages 42, the intake manifold jacket 40 and the pipe 43 thereby preventing, to a great extent, the loss of any of the heat generated by the engine, and using a part of it to heat the incoming combustible mixture, thereby aiding materially in starting the engine in cold weather. If the valve 39 is opened, a part of the cooling water will flow through the radiator and a part through the intake manifold jacket and associated passages, the proportion flowing through each depending upon several factors, including, as is obvious, the extent to which the valve is opened.

Though I have shown and described a specific embodiment of my invention, it is to be understood that this has been done merely by way of example, and not with the object of limiting my invention thereto, and that the scope of my invention is defined only by the appended claims.

I claim:

1. In an internal combustion engine having a cylinder and a cylinder head having therein a recess adapted to receive a cooling medium, means to conduct a cooling medium into the recess, and means extending into the recess and through which a portion of the cooling medium is adapted to be removed therefrom.

2. In an internal combustion engine having a cylinder and a cylinder head depending into the cylinder and having therein a recess adapted to contain a cooling medium, means to conduct a cooling medium into the recess, and means extending into the recess and through which a portion of the cooling medium is adapted to be removed from the recess.

3. The invention claimed in claim 2, and a fuel intake conduit, and means to conduct the cooling medium withdrawn from the recess through the second mentioned means around the intake conduit.

4. In an internal combustion engine having a cylinder and a cylinder head having a portion depending into the cylinder and having therein a recess, an intake manifold, a jacket around a portion of the intake manifold, means to conduct a cooling medium into the recess, means extending into the recess and through which a portion of the cooling medium is adapted to be withdrawn from the recess and conducted to the jacket, means adapted to conduct cooling medium from the recess to a cooling means, and means

adapted to withdraw cooling medium from the cooling means and the jacket and return it to the cooling means and the jacket.

5. The invention claimed in claim 4 and 5 means to regulate the flow of cooling medium through the cooling means.

6. In an internal combustion engine, a passage through which a cooling medium is adapted to be circulated to withdraw heat 10 from the engine, a passage through which a cooling medium is adapted to be conducted from the first-mentioned passage to a device in which heat is adapted to be extracted therefrom, a fuel intake passage, a passage 15 adjacent the fuel intake passage, a passage through which cooling medium is adapted to be conducted from the first-mentioned passage to the fourth-mentioned passage so that it gives up a portion of its heat to the fuel 20 intake passage, means for circulating cooling medium through said passages and device, and means for regulating the volume of the cooling medium which is conducted to said device and the fourth-mentioned passage.

7. In an internal combustion engine, a cylinder block water jacket, a cylinder head water jacket, a heating element, a passage for conducting cooling medium to the cylinder 30 block water jacket and the cylinder head water jacket, and a passage for conducting heated cooling medium from the cylinder head water jacket to the heating element.

8. In an internal combustion engine, a cylinder block water jacket, a cylinder head water jacket, a fuel intake passage, a passage adjacent the fuel intake passage, means to circulate cooling medium through the cylinder block water jacket and the cylinder 40 head water jacket and from the cylinder head water jacket through the second-mentioned passage and from the second-mentioned passage back to said circulating means.

9. In an internal combustion engine a cylinder block water jacket, a cylinder head water jacket, a heating element, means to circulate cooling medium through the cylinder block water jacket and the cylinder head water jacket, from the cylinder head water 50 jacket through the heating element, and from the heating element back to said circulating means, and a passage for conducting cooling medium from one of said water jackets through means in which heat is adapted to be extracted from the cooling medium and 55 back to said circulating means.

In testimony whereof I affix my signature.
ERIC OLLE SCHJÖLIN.
